FOREIGN PATENT DOCUMENTS

DE 3414388 A1 12/1985
FR 2535372 A1 5/1985*Primary Examiner* — Brett Miller*Assistant Examiner* — Sara Michie Pottenger(74) *Attorney, Agent, or Firm* — Carr & Ferrell LLP(57) **CLAIM**

The ornamental design for a tilt-up concrete side mold system, as shown and described.

DESCRIPTION

FIG. 1 is a perspective view of a tilt-up concrete side mold system showing my new design.

FIG. 2 is a top view thereof.

FIG. 3 is a bottom view thereof.

FIG. 4 is a left view thereof.

FIG. 5 is a right view thereof.

FIG. 6 is a front view thereof; and,

FIG. 7 is a rear view thereof.

The broken lines shown in the drawings are included for the purpose of illustrating environmental structure and form no part of the claimed design.

1 Claim, 5 Drawing Sheets(56)
